(57) **CLAIM**

The ornamental design for a platform for telescopic lifter, as shown and described.

DESCRIPTION

FIG. 1 is a top-front-right side perspective view of a platform for telescopic lifter, showing the new design;

FIG. 2 is a top view thereof;

FIG. 3 is a bottom view thereof;

FIG. 4 is a back view thereof;

FIG. 5 is a front view thereof;

FIG. 6 is a right side view thereof; and,

FIG. 7 is a left side view thereof.

The broken lines in the drawings are for the purpose of illustrating portions of the platform for telescopic lifter, which form no part of the claimed design. The additional broken lines in FIGS. 1-3 are to show environment and form no part of the claimed design.

1 Claim, 5 Drawing Sheets
